APPARATUS FOR AVOIDING MOISTURE CONDENSATION
ON TOILET FLUSH TANKS

Filed Jan. 3, 1949

UNITED STATES PATENT OFFICE

2,659,898

APPARATUS FOR AVOIDING MOISTURE CONDENSATION ON TOILET FLUSH TANKS

Robert W. Toye, Winona, Minn.

Application January 3, 1949, Serial No. 68,868

3 Claims. (Cl. 4—18)

1

This invention relates to a method of and apparatus for avoiding moisture condensation on toilet fixtures.

The invention is particularly concerned with a toilet flush tank and bowl, on which moisture condenses during the warm summer months and which runs down the tank and bowl and collects on the floor in unsightly and damaging puddles.

This condensation is caused by the cold water entering the toilet fixtures, whereby lowering the temperature thereof substantially below that of the humid air with the result that moisture in the air condenses on the outer surfaces of the toilet fixtures in drops which run down such surfaces and onto the floor.

This has become quite a nuisance to many housekeepers who find it necessary to frequently mop up the floor and possibly wipe the surfaces of the fixtures.

Methods have heretofore been provided to avoid collection of condensed moisture on the floor as by securing a tray beneath the toilet tank to catch the water, but no methods to my knowledge have heretofore been provided for eliminating the moisture condensation and thereby solving the whole nuisance problem.

It is accordingly a primary object of this invention to provide a method for effectively avoiding moisture condensation on toilet fixtures in warm humid weather.

A further object of the invention is to provide novel and simple apparatus for efficiently carrying the novel method into effect.

Other objects and advantages of the invention will become apparent in the course of the following detailed description, taken in connection with the accompanying drawing, wherein:

Fig. 1 is a front elevational view of a toilet tank and bowl and disclosing an operative association of the improved apparatus therewith.

Fig. 2 is a section through a novel form of valve structure included in the apparatus, the section being in the plane of line 2—2 on Fig. 3.

Fig. 3 is another section of the valve structure as observed in the plane of line 3—3 on Fig. 2.

Fig. 4 is a fragmental enlarged portion of Fig. 2 and showing the valve in section.

Fig. 5 is an elevational view of the novel valve structure and which together with Figs. 2 and 3 is full scale size.

Referring now in detail to the drawing, T designates a flush tank and B designates the bowl operatively associated therewith and into which water flows upon tripping of the control handle H.

2

The usual cold water tank supply pipe is indicated at P and such pipe is provided with the usual shut-off valve S.

The improved method consists in tempering the cold water entering the tank T through pipe P, or in raising the temperature of such cold water to approximately that of the atmosphere whereby the moisture in the atmosphere will not condense on the surface of the tank and bowl and in order to effect such method, the invention involves a novel valve structure 10 operatively connected in the cold water pipe P either above the shut-off valve S, or below as indicated.

The valve structure 10 comprises a housing 11 provided with opposite axially aligned threaded sockets 12 for receiving the ends of sections embodied in the cold water pipe P.

The sockets 12 communicate with relatively small bores 13 which are axially aligned with the sockets and which in turn communicate with a cylindrical valve opening 14 whose axis is transverse to that of sockets 12 and bores 13 and which opening terminates in a flat bottom wall 14' a substantial distance below the bores 13 and the opening opens through a projecting portion 11' of the housing.

The opening 14 communicates with another bore 15 whose axis is in the plane of the axis of the sockets and first bores. The bore 15 extends axially within an extension 16 of the housing and which merges into a further co-axial extension 17 which is externally threaded and is provided with a bore 18 somewhat larger than and co-axial with bore 15.

A length of tubing 20 which is adapted to extend to and be in communication with a constant hot water supply has an internal diameter equal to the diameter of bore 18 and an end of such tubing abuts the end of extension 17 and is secured in position by means of a nut 19, the tubing having a bevelled end portion 20' clamped between corresponding bevels on the extension 17 and nut 19.

A cylindrical valve 21 is supported in opening 14 for rotation about its axis. The valve includes an integral co-axial stem 22 of reduced diameter whereby providing a circular shoulder 21' on the valve and the valve is removably maintained in the opening 14 by means of a nut 23 within which is compressed a packing 24 which seals the valve against leaking as well as providing sufficient friction for maintaining the valve in any predetermined adjusted position about its axis.

The valve stem 22 is fluted as at 25 and is re-

ceived in a fluted opening in the hub 26 of a handle 27. The handle is releasably held on the stem by means of a screw 28 which draws the fluted hub onto the slightly bevelled fluted end of the stem 22.

The handle hub 26 is provided with a threaded socket 29 whose bottom provides a shoulder for the head of screw 28 and a nut 30 is threaded into the socket. The nut 30 is provided with a central threaded bore 31 for receiving a screw 32 which frictionally holds a pointer 33 in any desired set position.

The lower end of valve 21 seats on the bottom walls 14' of opening 14 and the valve is cut out at 34 providing a substantial passage adjacent the plane of bores 13 and 15 and the cut out provides a segment 35 as is clearly indicated in Fig. 4.

The lower end of the valve is provided with a concentric channel 36 of substantially 180° extent and a pin 37 or other projection from the bottom wall 14' of opening 14 is engaged in said channel, the cooperating pin and channel providing for rotation of the valve and the valve being limited in its rotation by engagement of the pin with one or the other of the ends of the channel.

The improved valve structure as above described may easily be incorporated in the cold water supply pipe P by a plumber and the conduit 20 is extended to a constant hot water supply as for example an automatic gas heated tank which at present exists in most homes.

In assembling the apparatus, the hot water admission bore or port 15 will always be open to the cut out 34 in the valve and the valve will be rotated to such extent that the flow of cold water through bores or ports 13 will be controlled by the segment 35 which in Fig. 4 is shown as closing substantially one half of a port 13. By proper adjustment of the valve the water entering the tank may be kept at about 80° F. which would approximate that of the atmosphere in summer months.

When the valve has been set for the proper temperature, the pointer 33 will be set extending upwardly in the axis of pipe P as indicated in Fig. 1. Should the weather become less humid the valve may be turned clockwise until pin 37 engages one end of channel 36 and in which position the port 15 will be closed thereby saving hot water and should the humid weather return, the valve may be turned counterclockwise to a position wherein the pointer again alines with pipe P as in Fig. 1.

While I have disclosed my invention in accordance with a single specific embodiment thereof, such is to be considered as illustrative only and not restrictive, the scope of the invention being defined in the sub-joined claims.

What I claim and desire to secure by U. S. Letters Patent is:

1. Apparatus for tempering cold water admitted through a supply pipe to a flush tank whereby to raise the temperature of the external wall of the tank to prevent condensation of moisture from a humid atmosphere thereon, which comprises a valve structure in the supply pipe, a conduit extending from a hot water source and having an end thereof connected to and in communication with the valve structure and a valve in such structure operative to vary the relative volumes of hot and cold water passing through the valve structure and supply pipe to the tank, said valve structure comprises a housing having an elongated cylindrical valve receiving opening therein and which is closed at one end by a flat wall, the housing having axially aligned threaded sockets for connection in the supply pipe, axially aligned ports communicating with said sockets and said opening above said bottom wall, the said opening and ports providing for passage of cold water through the valve structure, a further port having one end thereof communicating with said opening and having its axis at right angles to the axes of said first ports and in the plane of said axis, a hot water supply conduit communicating with the other end of said last port, and said valve being of cylindrical form and being rotatably supported in said opening and including a relief and a segment adjacent the plane of said ports for controlling the relative volumes of hot and cold water passing through the valve structure.

2. The structure according to claim 1 wherein the inner end of said cylindrical valve is provided with a circular channel having closed ends, a pin projecting from said flat wall and engaged in said channel, and said pin being engageable with one or the other of said channel ends to limit rotary adjustment of the valve in clockwise and counter-clockwise direction.

3. The structure according to claim 1 wherein said valve is provided with a coaxial stem, a handle removably supported by the stem, and a pointer adjustably supported by the handle.

ROBERT W. TOYE.
